(57) **CLAIM**

The ornamental design for a foldable triangular warning sign, as shown and described.

DESCRIPTION

FIG. 1 is a perspective view of a foldable triangular warning sign showing a first embodiment of our new design; FIG. 2 is a front view of the first embodiment; FIG. 3 is a rear view of the first embodiment; FIG. 4 is a left side view of the first embodiment; FIG. 5 is a right side view of the first embodiment; FIG. 6 is a top view of the first embodiment; FIG. 7 is a bottom view of the first embodiment; FIG. 8 is a perspective view of the first embodiment in the folded state; FIG. 9 is a perspective view of a foldable triangular warning sign showing a second embodiment of our new design; FIG. 10 is a front view of the first embodiment; FIG. 11 is a rear view of the second embodiment; FIG. 12 is a left side view of the second embodiment; FIG. 13 is a right side view of the second embodiment; FIG. 14 is a top view of the second embodiment; FIG. 15 is a bottom view of the second embodiment; and, FIG. 16 is a perspective view of the second embodiment in the folded state. The dashed broken lines illustrate portions of the foldable triangular warning sign and form no part of the claimed design.
